HOIST CONTROL

Frank E. Stahl, deceased, late of Tonawanda, N. Y., by Lillie M. Stahl, administratrix, Tonawanda, N. Y., and Alfred Cotesworth, Kenmore, N. Y., assignors to Columbus McKinnon Chain Corporation, Tonawanda, N. Y., a corporation of New York

Application December 23, 1933, Serial No. 247,373

5 Claims. (Cl. 74—470)

Our invention relates in general to hoist controls and particularly to the controls of the electric type hoist in which an electric motor forms an integral part of the hoist structure and which is controlled by manually operated pull cords.

It is well known to those skilled in the art that in order to manufacture an inexpensive electric hoist, it is necessary to use an inexpensive electric motor, which limits the manufacturer to the use of a motor of the single-phase, split-phase type, or the capacitor type. When such type of motor is used, however, it is necessary that some means be provided for preventing too rapid operation of the controller switch in effecting a reversal of the motor shaft since, unless the motor shaft is allowed to come to a standstill before the reverse switch is thrown to its operative position, the motor shaft and armature will continue to rotate in the direction first operated.

One of the principal objects of our invention has been, therefore, to provide a control for an electric hoist, equipped with such type motor, which will cause a delay in the operation of the controller switch from one direction of rotation of the motor to the other direction, during which delay the motor shaft will have had time to come to a standstill.

Another object has been to provide a device which may be easily applied to existing hoists without the necessity of altering or redesigning such hoist.

Moreover, it has been an object to provide a device of this nature which can be operated by a single pull cord.

Furthermore, our invention is inexpensive to manufacture and does not, therefore, add materially to the cost of the entire hoist.

The above objects and advantages have been accomplished by the device shown in the accompanying drawing, of which:

Fig. 1 is a side elevation of a complete electric hoist equipped with our invention.

Fig. 2 is a fragmentary, end elevation of our improved device.

Fig. 3 is a fragmentary, sectional, side elevation thereof taken on line 3—3 of Fig. 2.

In the drawing, 5 represents the hoist which is provided with an electric motor 6 and a controller switch 7. The casing of the hoist is represented at 8, to which the motor is attached. The cover of the casing is represented at 9.

The control shaft 10 of our device is rotatably carried by the casing of the hoist and it is provided with an enlarged head 11. The control

lever 13 is provided with a hub 14, which hub is rotatably mounted upon the head 11 of the control shaft. The lever is held against outward axial movement upon the head by means of a washer 12. The washer is secured in position against the head preferably by means of a bolt 34. The lever is held against inward axial movement on said head by means of a collar 35 formed preferably on said head.

10 The control lever of our device is provided with a control arm 15 arranged to lie in substantially a horizontal plane when the lever is in neutral position. This arm is attached to the hub 14 and is positioned preferably at or below the axis of 15 the hub, and substantially at or below the lower periphery of the hub. It is centrally arranged with respect to the axis of the hub and is provided with a slot 16 of substantially arcuate or wide V-shape formation. This slot is bounded 20 preferably on the upper side by an arcuate surface 17 and on the bottom side by inclined surfaces 18 which meet and join each other substantially at the center of the arm. At the extreme outer ends of the arm the surfaces 17 and 18 are joined together by a circular surface 19. This surface is arranged to have its lower periphery slightly below the inclined surface 18 whereby a slight recess 20 is provided, to be hereinafter described. A trolley 21 is carried 25 by the control lever and a roller 22 is rotatably supported thereby. The trolley is preferably of U-shape formation, as shown in Fig. 3, and the roller is so mounted as to engage with the inclined surfaces 18 and the recesses 20. Our invention contemplates the use of but one operating cord 23 which is attached to the trolley 21 and carries at its lower end an operating handle 24.

30 The control lever 13 is mounted for a limited amount of free movement upon the head 11 of the control shaft, and this is accomplished by providing the hub 14 of the lever with an arcuate groove 25, having its radii struck from the axis of the hub and providing abutment shoulders 26 and 27 at the ends thereof. A detent key 28 is carried by the head 11 and projects into the slot 25, in which position it will be engageable with either the abutment shoulder 26 or 27.

35 The control lever is preferably held in its neutral position by means of a centralizing spring 29 which has its upwardly extending ends 30 engageable with a lug 31 carried by the cover or casing 9 of the hoist and a lug or pin 32 carried by an upstanding arm 33 provided on the hub 14 of the control lever.

When it is desired to operate a hoist equipped with our device, the handle 24 at the bottom of the operating cord 23 is grasped and the trolley 21 is moved through the groove 16 to either end of the arm 15 of the control lever. If, for instance, the load is to be elevated, the trolley will be moved to the right-hand end of the arm, as viewed in Fig. 2, and the roller thereof will drop into the recess 20 when it reaches the end of the surface 18, whereupon the operator then pulls the cord downwardly which will cause this end of the arm to be depressed. During such movement, the lever is free to rotate idly upon the head 11 and the slot 25 carried by the hub 14 of the lever will be moved around over the detent key 23 until the abutment shoulder 26 is reached. When this shoulder is brought in contact with the key 28, the head 11 and the control shaft 10 will be positively operated to cause the controller switch 7 to be operated in the proper direction. When the hoist is now to be operated in the reverse direction, and the load is to be lowered, the operator releases his pull upon the operating cord 23, allowing the control lever to be returned to its neutral position by means of the centralizing spring 29, and the controller switch 7 to return to its neutral position under the tension of the centralizing spring usually provided with such switches (not shown). The roller 22 of the trolley 21 is then removed from the recess 20 by a slight side-wise jerking movement of the control cord to the left of Fig. 2, which will cause the roller 22 to be released from the recess and allow the trolley to ride down the inclined surface 18 at the right-hand side of the arm. The operator may now move the trolley toward the left (as viewed in Fig. 2), causing it to ride over the inclined surface 18 at the left-hand end of the control arm 15 until the roller 22 reaches the recess 20 in that end of the arm. During the return movement of the control arm to its neutral position, the slot 25 has moved idly over the key 28 and now, upon again pulling the cord 23, the left-hand end of the arm 15 of the control lever will be depressed, which will cause the slot 25 to ride over the detent key 28 until the abutment shoulder 27 has been reached, after which the head 11 and the control shaft 10 will be positively operated in counterclockwise direction to operate the controller switch.

The time required to bring the control lever 13 back to its neutral position and to move the trolley through the groove 16 to the other extreme end of the arm, in addition to the lost motion between the abutment shoulders of the groove 25 and the detent key 28, will provide sufficient time for the motor of the hoist to come to a standstill before the controller switch can be operated to reverse the direction of rotation of the motor shaft. Obviously, instead of the inclined surfaces 18, the lower side of the groove 16 may be bounded by an arcuate or curved surface.

These and other modifications of the details herein shown and described may be made without departing from the spirit of our invention or the scope of the appended claims, and we do not, therefore, wish to be limited to the exact embodiment herein shown and described, the form shown being merely a preferred embodiment thereof.

Having thus described our invention, what we claim is:

1. A control for single-phase, reversing electric

motors of the type which continues its operation uni-directionally upon too rapid operation of the reversing means, comprising a control member freely movable in two directions, a manually actuated control lever oscillatably mounted substantially midway its length upon said control member, said control lever having outwardly and oppositely extending arms projecting one from each side thereof, each arm being formed with an operating surface, the surface of each arm meeting and joining the surface of the other arm, control means slidably mounted upon the operating surfaces of said control lever, and an operating rope connected to said control means.

2. A control for single-phase, reversing electric motors of the type which continues its operation uni-directionally upon too rapid operation of the reversing means, comprising a control member freely movable in two directions, a manually actuated control lever oscillatably mounted substantially midway its length upon said control member, said control lever having outwardly and oppositely extending arms projecting one from each side thereof, each arm being formed with an operating surface, the surface of each arm meeting and joining the surface of the other arm, each of said surfaces being formed with a recess at its opposite extremity, control means slidably mounted upon the operating surfaces of said control levers for alternate engagement with said recesses, and an operating rope connected to said control means.

3. A control for single-phase, reversing electric motors of the type which continues its operation uni-directionally upon too rapid operation of the reversing means, comprising a control shaft freely movable in two directions, a manually actuated control lever oscillatably mounted substantially midway its length upon said control shaft, said control lever having outwardly and oppositely extending arms projecting one from each side thereof, each arm being formed with an inclined operating surface, the surface of each arm being inclined in the opposite direction and meeting and joining the surface of the other arm, control means slidably mounted upon the operating surfaces of said control levers, and an operating rope connected to said control means.

4. A control for single-phase, reversing electric motors of the type which continues its operation uni-directionally upon too rapid operation of the reversing means, comprising a control member freely movable in two directions, a manually actuated control member oscillatably mounted substantially midway its length upon said control lever for idle relative movement therewith through a limited arcuate path in either direction to its actuating position, said control lever being adapted to be moved in either direction by means of a single operating rope, said control lever having outwardly and oppositely extending arms projecting one from each side thereof, each arm being formed with an inclined operating surface, the surface of each arm being inclined in the opposite direction and meeting and joining the surface of the other arm, control means connected to said operating rope and slidably mounted upon the operating surfaces of said control lever, and interspaced detent means carried by said control shaft and said control lever for coupling said shaft and said lever at the extremities of said idle relative movement to positively actuate said shaft to either actuating position.

5. A control for single-phase, reversing electric motors of the type which continues its operation uni-directionally upon too rapid operation of the reversing means, comprising a control member freely movable in two directions, a manually actuated control lever oscillatably mounted substantially midway its length upon said control member for idle relative movement therewith through a limited arcuate path in either direction to its actuating position, said control lever being adapted to be moved in either direction by means of a single operating rope, said control lever having outwardly and oppositely extending arms projecting one from each side thereof, each arm being formed with an inclined operating surface, the surface of each

5 arm being inclined in the opposite direction and meeting and joining the surface of the other arm, each of said surfaces being formed with a recess at its outer extremity, control means connected to said operating rope and slidably mounted upon the operating surfaces of said control lever and alternately engageable with said recesses, and interspaced detent means carried by said control shaft and said control lever for coupling said shaft and said lever at the extremities of said idle relative movement to positively actuate said shaft to either actuating position.
